UNITED STATES PATENT OFFICE.

CHARLES F. PURDIE, OF DETROIT, MICHIGAN.

CAPSULE-MACHINE.

SPECIFICATION forming part of Letters Patent No. 276,282, dated April 24, 1883.

Application filed September 29, 1882. (No model.)

To all whom it may concern:

Be it known that I, CHARLES F. PURDIE, of Detroit, county of Wayne, State of Michigan, have invented a new and useful Improvement 5 in Capsule-Machines; and I declare the following to be a full, clear, and exact description of the same, such as will enable others skilled in the art to which it pertains to make and use it, reference being had to the accompanying 10 drawings, which form a part of this specification.

My invention consists in the combinations of devices and appliances hereinafter specified, and more particularly pointed out in the claims.

15 In the drawings, Figure 1 is a side elevation of a device embodying my invention. Fig. 2 is a plan view of a portion of the same. Fig. 3 is a variation. Fig. 4 is a perspective view of a mold or pin.

20 My invention is designed as an improvement upon a device for which an application for Letters Patent was filed by me August 26, 1882, (Serial No. 70,356,) for a capsule-machine, and is designed especially to provide means whereby 25 the plate to which the capsule-molds are commonly attached may be dispensed with. I accomplish this result, first, by holding the molds in place by means of a wire fastening; and, second, by providing means for removing 30 the molds from the capsules independent of said mold-plate.

In carrying out my invention, A is a plate provided with one or more perforations, *a*, adapted to receive a capsule-mold. Said perforations may simply extend through said 35 plate even with the surface, or be extended by a hub rigidly secured thereto; or the plate may be provided with suitable bushing for said perforations, as may be desired.

40 B represents one or more capsule-molds, preferably encircled by a suitable depression or groove, *b*. Said molds are provided with a socket, *b'*, and a T-shaped head, *b''*.

B' represents wire inserted in the sockets *b'*, 45 by means of which two or more molds may be secured together. I prefer that said sockets should be constructed eccentrically, and that the pins should be so arranged that the sockets will be alternately on opposite sides of the 50 center in order that the wire may be passed in

a zigzag manner through the series of molds, as shown in Fig. 3, as the molds will thus be more securely held together.

B'' represents capsules formed upon the molds B.

C is a plate provided with T-shaped sockets *c*, adapted to engage with the T-shaped heads of the molds.

In order to remove the molds from the capsules, it is evident that the plate A may be forced 60 downward by any proper mechanism; or the plate C, when the heads *b''* of the molds have been engaged in the sockets *c*, may be forced upward by any suitable means. As shown in the drawings, the plate C is adapted to be 65 forced upward, and for this purpose is sleeved upon the guides D. In order to distribute the strain upon the sleeved plates and secure a more perfect vertical movement of the mold-pins when the plate C is forced upward, I prefer 70 to provide the plate E with additional arms, F, rigidly secured thereto and sleeved in the plate C, said arms extending through upon the sleeved plate for the purpose of holding it firmly down when the molds are removed.

The operation of the device will now be understood. After the molds, secured together in the sleeved plate A in the manner described, have been dipped in the gelatine and the capsules formed thereon and suitably dried, said 80 plate is secured in the frame G, provided with suitable guides therefor. At the same time the heads of the molds are engaged in the sockets of the plate C, when by lifting said plate C by any proper mechanism the molds are 85 withdrawn from the capsules, and the sleeves of the plate A cut the capsules on the lower exterior of the groove *b* in the manner described in the application already referred to.

I would have it understood that I do not confine myself to the T-shaped head for the capsule-molds or the corresponding T-shaped sockets in the plate C, as it is evident that any other suitable shape of the same would answer the same purpose.

It is evident, also, that suitable hooks might be provided to grip upon the heads of the molds for the purpose of their removal from the capsules.

H is a capsule-mold, whose cross-section is 100

elliptical or oval in form. Said pin is preferably encircled with the groove *h*. The object of constructing the mold elliptical or oval in cross-section is to impart a corresponding shape to 5 the completed capsule. This form is advantageous, in that it enables the capsule to be more readily and easily swallowed than where the capsule is in the form of a cylinder. A is a plate provided with one or more oval perforations or sockets adapted to receive said mold. It is evident that a capsule formed upon such a mold possesses superior advantages over those in common use; but I would have it understood that I do not confine myself to any 10 particular shape of molds.

15 I do not herein broadly claim a plate provided with sockets or sleeves, and mold-pins arranged to be reciprocated through such sockets or sleeves, as such features constitute 20 the subject-matter of the application for Letters Patent hereinbefore referred to.

What I claim is—

1. In a capsule-machine, the combination, 25 with a perforated plate, of one or more capsule-molds adapted to be projected to and fro in said perforated plate by any suitable mechanism, a plate engaging the heads of the capsule-molds, said molds being secured together by a wire fastening, substantially as and for 30 the purpose described.

2. In a capsule-machine, the combination, 35 with a sleeved plate, of one or more capsule-molds adapted to be projected to and fro in said sleeved plate by any suitable mechanism, said molds engaged at their butt-ends by a suitable grooved plate, substantially as and for 40 the purpose described.

3. In a capsule-machine, the combination, 45 with a sleeved plate, of one or more capsule-molds adapted to be projected to and fro in said sleeved plate by any suitable mechanism,

said molds engaged at their butt-ends by a suitable grooved plate, and secured together by a wire fastening, substantially as and for the purpose described.

4. In a capsule-machine, the combination, 45 with a sleeved plate, of one or more capsule-molds adapted to be projected to and fro in said sleeved plate by any suitable mechanism, said molds provided at a capsule length from 50 the end of the molds with annular grooves, and the butt-ends of the molds fastened together by a wire, substantially as described.

5. In a capsule-machine, a series of capsule-molds secured together by a wire fastening, 55 substantially as and for the purpose described.

6. In a capsule-machine, the combination of a series of capsule-molds united by a wire connection, and a plate constructed to be engaged with and disengaged from the ends of the 60 molds, substantially as and for the purposes described.

7. In a capsule-machine, the combination, 65 with a sleeved plate, of a series of capsule-molds secured together by a wire fastening, a plate adapted to engage with said molds and to project them to and fro in said sleeved plate by any suitable mechanism, a frame adapted to receive said sleeved plate, suitable guides for the mold-removing plate, and additional 70 arms, F, substantially as and for the purpose described.

8. In a capsule-machine, a mold-pin whose cross-section is of oval form, substantially as and for the purpose described.

In testimony whereof I sign this specification in the presence of two witnesses.

CHARLES F. PURDIE.
